(57) **CLAIM**

The ornamental design for a combined bookmark and pen, as shown and described.

DESCRIPTION

FIG. 1 is a perspective view of a combined bookmark and pen showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the bottom plan view shown in FIG. 8.

The broken lines in the drawings depict portions of the combined bookmark and pen that form no part of the claimed design.
